CLAIM

The ornamental design for a display screen or portion thereof with animated graphical user interface, as shown and described.

DESCRIPTION

FIG. 1 is a front view of a display screen or portion thereof showing the first image of a sequence of images of the animated graphical user interface;

FIG. 2 is a front view of the display screen or portion thereof showing the second image of the sequence of FIG. 1;

FIG. 3 is a front view of the display screen or portion thereof showing the third image of the sequence of FIG. 1;

FIG. 4 is a front view of the display screen or portion thereof showing the fourth image of the sequence of FIG. 1;

FIG. 5 is a front view of the display screen or portion thereof showing the fifth image of the sequence of FIG. 1;

FIG. 6 is a front view of the display screen or portion thereof showing the sixth image of the sequence of FIG. 1;

FIG. 7 is a front view of the display screen or portion thereof showing the seventh image of the sequence of FIG. 1;

FIG. 8 is a front view of the display screen or portion thereof showing the eighth image of the sequence of FIG. 1;

FIG. 9 is a front view of the display screen or portion thereof showing the ninth image of the sequence of FIG. 1;

FIG. 10 is a front view of the display screen or portion thereof showing the tenth image of the sequence of FIG. 1;

FIG. 11 is a front view of the display screen or portion thereof showing the eleventh image of the sequence of FIG. 1;

FIG. 12 is a front view of the display screen or portion thereof showing the twelfth image of the sequence of FIG. 1;

FIG. 13 is a front view of the display screen or portion thereof showing the thirteenth image of the sequence of FIG. 1;

FIG. 14 is a front view of the display screen or portion thereof showing the fourteenth image of the sequence of FIG. 1;

FIG. 15 is a front view of the display screen or portion thereof showing the fifteenth image of the sequence of FIG. 1;

(Continued)

FIG. 16 is a front view of the display screen or portion thereof showing the sixteenth image of the sequence of FIG. 1;

FIG. 17 is a front view of the display screen or portion thereof showing the seventeenth image of the sequence of FIG. 1;

FIG. 18 is a front view of the display screen or portion thereof showing the eighteenth image of the sequence of FIG. 1;

FIG. 19 is a front view of the display screen or portion thereof showing the nineteenth image of the sequence of FIG. 1;

FIG. 20 is a front view of the display screen or portion thereof showing the twentieth image of the sequence of FIG. 1;

FIG. 21 is a front view of the display screen or portion thereof showing the twenty-first image of the sequence of FIG. 1;

FIG. 22 is a front view of the display screen or portion thereof showing the twenty-second image of the sequence of FIG. 1;

FIG. 23 is a front view of the display screen or portion thereof showing the twenty-third image of the sequence of FIG. 1;

FIG. 24 is a front view of the display screen or portion thereof showing the twenty-fourth image of the sequence of FIG. 1;

FIG. 25 is a front view of the display screen or portion thereof showing the twenty-fifth image of the sequence of FIG. 1;

FIG. 26 is a front view of the display screen or portion thereof showing the twenty-sixth image of the sequence of FIG. 1; and,

FIG. 27 is a front view of the display screen or portion thereof showing the twenty-seventh image of the sequence of FIG. 1.

FIGS. 1-27 depict a sequence of images for a display screen or portion thereof with animated graphical interface showing our new design. The appearance of the transitional image sequentially transitions between the images of the sequences shown in FIGS. 1-27. The process or period in which one image transitions to another forms no part of the claimed design. The broken lines in the Figures show remainders of the graphical user interface and the display screen or portion thereof and form no part of the claimed design.
